UNITED STATES PATENT OFFICE.

MICHAEL SETTER, OF CHICAGO, ILLINOIS, ASSIGNOR TO AUTOMATIC ELECTRIC COMPANY, OF CHICAGO, ILLINOIS, A CORPORATION OF ILLINOIS.

DESIGN FOR A CASING FOR HAND-TELEPHONES.

46,267.

Specification for Design.

Patented Aug. 11, 1914.

Application filed June 5, 1913. Serial No. 772,008. Term of patent 14 years.

To all whom it may concern:

Be it known that I, MICHAEL SETTER, a citizen of the United States of America, residing at Chicago, in the county of Cook and State of Illinois, have invented a new, original, and ornamental Design for a Casing for Hand-Telephones, of which the following is a specification, reference being had to the accompanying drawings, forming part thereof.

Figure 1 is a plan view of my improved

design for hand telephones. Fig. 2 is a front elevation of the same. Fig. 3 is a bottom view of the same.

I claim:

The ornamental design for a casing for a hand telephone, as shown.

MICHAEL SETTER.
